UNITED STATES PATENT OFFICE

FREEBORN F. RAYMOND, 2d, OF NEWTON, MASSACHUSETTS.

HEEL FORMING AND ATTACHING MACHINE.

SPECIFICATION forming part of Letters Patent No. 378,216, dated February 21, 1883.

Application filed November 21, 1887. Serial No. 255,678. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Boot and Shoe Heel Forming and Attaching Machines, of which the following is a full, clear, and exact description, reference being had to the accompanying drawings, forming a part of this specification, in explaining its nature.

The invention relates to an organized heel-nailing machine or heel-forming machine having a die-block for forming the sides of the heel-blank, (either detached from the soles of the boot or shoe or while it is being attached to said soles,) sections of which die-block are made movable for the purpose of varying the size of the die.

It also relates to the said die-block and the parts thereof, and means whereby the adjustments of its section are obtained.

In the drawings, Figure 1 is a view, part in elevation and part in vertical section, of the central and upper portions of a machine having the features of my invention, the vertical section being taken upon the dotted line yy of Fig. 2. Fig. 2 is a view in horizontal section upon the dotted line xx of Fig. 1. Fig. 3 is a view partially in elevation, a die-block being broken out, to show the relation of the parts to each other during the forming or compressing of the heel-blank upon the soles of the boot or shoe. Fig. 4 is a view, part in elevation and part in vertical section, illustrating a slight modification. Figs. 5, 6, 7, and 8 also illustrate modified forms of a portion of the invention, to which reference will hereinafter be made. Fig. 9 is a plan view of the table supporting the templet and die.

Referring to the drawings, A represents the cross-head of the machine, which, preferably, is provided with a reciprocating movement, substantially as described in United States Patent No. 316,894. It supports a revolving head, a , having, preferably, the arm a' , which carries the presser-block a^2 , the arm a^3 , supporting a block, a^4 , carrying the awls a^5 , arm a^6 , having a block, a^7 , supporting the drivers a^8 , and an arm, a^9 , having a spanner-block, a^{10} , which may also have top-lift folding devices.

B is the vertically-movable table which sup-

ports the die-block C, templet D, and the nail-carrier E. It has a long sleeve, b , which is mounted upon the post b' . It has the extensions b^2 , which support the die-block C, and the guideway b^3 for the templet. The templet has a horizontal movement in this guideway, and with the nail-carrier E is secured to the bed by cap-plates b^4 . The extensions b^2 have side recesses, b^5 , for holding the die-block, and the die-block is fastened to these extensions beneath the templet by means of the spring-pin or in any other desirable way.

The die-block comprises the block C, which is preferably shaped as represented in Fig. 1—that is, it has the recesses c^2 , which receive the sections $c^3 c^4$ of the die, the said recesses being formed with the shoulders $c^5 c^6$, the first of which acts as a support for the flange c^7 upon each of the two sections $c^3 c^4$ of the die, and the second of which acts as a support for the lower edge of these sections. (See Fig. 1.) These sections $c^3 c^4$ of the die are horizontally adjustable in said recesses c^2 in relation to each other, whereby the width of the die-cavity c^8 may be varied as desired. This adjustment is obtained by means of adjusting or setting screws c^9 , of which there are preferably two upon each side of the die-block. These screws extend through screw-holes in the die-block, and their ends bear against the sections $c^3 c^4$ of the dies and form abutments or supports for holding the sections of the die in the die-block, and the width of the die-cavity varies according as these screws are set in or out. This construction provides for the adjustment of the width of the die cavity or recess. For the adjustment of the length of the die cavity or recess I employ a die-section, c^{10} , the inner surface, c^{11} , of which forms the front wall of the die-cavity. (See Fig. 2.) This section is formed of the metal plate, and is adjustable lengthwise the die-cavity to increase or diminish the length thereof by means of the adjusting or setting screws c^{12} , which pass through it into the block C, (see Fig. 2;) and it will be seen that by changing the position of this plate c^{10} in relation to the die-block C the length of the die cavity or recess c^8 is made variable.

Where the heel-blank is molded upon the sole of the boot or shoe, it is desirable that the front section, c^{11} , of the die be vertically

movable during the compression of the heel-blank, in order that it may not injure the outsole of the boot or shoe as the heel-blank is compressed and varied in height; and this feature of the invention may be used in a die otherwise solid, as represented in Figs. 5, 6, 7, and 8, or in a die the length of which is adapted to be varied, as above specified. To accomplish it, the section which forms the front of the die is provided with a vertical movement in the vertical guideways c^3 or recesses formed in the die-block, as represented in Figs. 5 to 8, or in the movable section of the die-block, as represented in Fig. 2. This upward movement of the section c^1 must be substantially unrestricted, and consequently the templet-plate must be so formed as to extend to the front edge of the die-cavity, as shown in Fig. 7; or, if it extends over it, it must have a recess into which the said vertically-movable section of the die-cavity can be moved. This section may drop to its normal condition upon the removal of the compressed heel-blank, by gravity, or it may be returned thereto by means of the spring d . (See Figs. 7 and 8.)

When the machine has a die having all the adjustments above described, the die is first set to the size of the completed heel which it is desired to form, and the heel-blank is inserted in the die-cavity from below. The templet-plate is moved into position over the die-block and die-cavity, and the die-block and the templet are moved forcibly downward by the presser-block a^2 upon a reciprocation of the head A , and the templet and die-block locked in their depressed condition. The pressure-block is then moved out of position and the awls into position and reciprocated, forming the holes in the heel-blank. The awls are then moved out of position, the drivers brought into position, and nails conveyed to the holes of the templet by the nail-carrier, the reciprocation of the drivers driving the nails into the heel-blank and soles of the boot or shoe, if it is then desired to attach the heel-blank to the boot or shoe; and if the heel-blank is to be blind-nailed the templet and die are released, the heel-blank freed from the die, the templet withdrawn, and the spanker brought into position and provided with a top lift and reciprocated. I would say that by this means a die is provided which may be increased or varied in width only, or in length only, or both in width and in length.

In Fig. 4 I show the die-block as made integral with the table B instead of separate from it, as represented in Fig. 1, and the die-sections c^3 are made adjustable therein by screws c^9 , and the front plate, c^{10} , is made hori-

zontally adjustable in relation to the sections c^3 c^4 ; but instead of attaching it to the die-block or the equivalent therefor I prefer to attach it by its screws c^{12} to the face of the die-sections c^3 c^4 .

Having thus fully described my invention, I claim and desire to secure by Letters Patent of the United States—

1. The combination, in a heel attaching or forming machine, of the templet, a die-block, and the die-sections c^3 c^4 , horizontally adjustable in relation to each other in the die-block, substantially as described.

2. In a heel attaching or forming machine, a die-block and the die-sections c^3 c^4 , horizontally adjustable in the die-block, substantially as described.

3. In a heel attaching or forming machine, the combination of a die with a plate or block, c^1 , a surface of which forms the breast end of the die and which is adjustable lengthwise the die for the purpose of increasing the length of the die, as and for the purposes described.

4. In a heel attaching and forming machine, a die having the vertically-movable breast plate or block, as and for the purposes described.

5. In a heel attaching or forming machine, the combination of the die-block C , the sections c^3 c^4 of a die supported thereby, and the adjusting-screws c^9 , substantially as described.

6. The combination, in a heel attaching or forming machine, of the die-block having the shoulders c^5 c^6 , with the die sections c^3 c^4 , having the flanges c^7 , and the screws c^9 , substantially as described.

7. The combination, in a heel attaching or forming machine, of the die-block or die, the plate or block c^{10} , and the adjusting-screws c^{12} , substantially as described.

8. The combination, in a heel attaching or forming machine, of the die-block C , the die-sections c^3 c^4 , their adjusting-screws c^9 , the breast plate or block c^{10} , and their adjusting-screws c^{12} , substantially as described.

9. The combination, in a heel attaching or forming machine, of a vertically-movable table, a templet carried by the said table, a die-block also supported by said table, a sectional die supported by said die-block and adjustable as to size, a support for the boot or shoe or heel blank, and a pressure-block, a gang of awls, and gang of drivers adapted to be brought successively into operative position and to be reciprocated, substantially as described.
